CLAIM

I claim the ornamental design for a sports helmet, as shown and described.

DESCRIPTION

FIG. 1 is a perspective view of a sports helmet showing my new design;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a perspective view of a second embodiment thereof;

FIG. 7 is a right side elevational view thereof, the left side being a mirror image;

FIG. 8 is a front elevational view thereof;

FIG. 9 is a rear elevational view thereof; and,

FIG. 10 is a top plan view thereof.

The strap shown in broken lines in FIGS. 1-4 and 6-9 is shown for illustrative purposes only and forms no part of the claimed design.
